To all whom it may concern:

Be it known that I, JOHN D. STUART, a citizen of the United States, residing at South Euclid, in the county of Cuyahoga and State of Ohio, have invented a new, original, and ornamental design for a Manicuring Machine, of which the following is a specification, reference being had to the accompanying drawings, forming a part thereof.

In the drawings, Fig. 1 is a side elevation

of the manicuring machine; Fig. 2 is a plan thereof;—each view showing the flexible shaft in its normal position of rest, and with the movable electric light bracket in one of its usual positions.

I claim:

The ornamental design for a manicuring machine, substantially as shown and described.

JOHN D. STUART.
